UNITED STATES PATENT OFFICE.

WILLIAM W. HOBE, OF NEW YORK, N. Y.

DESIGN FOR AN APPLIQUÉ TRIMMING.

Application filed February 28, 1927. Serial No. 20,909. Term of patent 3½ years.

To all whom it may concern:

Be it known that WILLIAM W. HOBE, a citizen of the United States, and resident of New York city, in the county of New York and State of New York, has invented a new, original, and ornamental Design for an Appliquéd Trimming, of which the following is a specification, reference being had to the accompanying drawing, forming part thereof, in which,—

Fig. 1 is a plan view of the trimming embodying my new design; and
Fig. 2 is an edge elevational view thereof.

I claim:
The ornamental design for an appliquéd trimming, as shown.

Dated New York, N. Y., February 23, 1927.

WILLIAM W. HOBE.
